UNITED STATES PATENT OFFICE.

CHESTER MCNEIL AND DUDLEY S. SEYMOUR, OF CHICAGO, ILLINOIS, ASSIGNEES TO UNION SPECIAL MACHINE COMPANY, OF CHICAGO, ILLINOIS, A CORPORATION OF ILLINOIS.

BAG SEAMING, CUTTING, AND DELIVERING APPARATUS.

No. 875,591.

Specification of Letters Patent.

Patented Dec. 31, 1907.

Application filed November 21, 1905. Serial No. 288,466.

To all whom it may concern:

Be it known that we, CHESTER MCNEIL and DUDLEY S. SEYMOUR, citizens of the United States, residing at Chicago, in the county of Cook, State of Illinois, have invented certain new and useful Improvements in Bag Seaming, Cutting, and Delivering Apparatus, of which the following is a description, reference being had to the accompanying drawing and to the letters and figures of reference marked thereon.

The invention relates to an improvement in apparatus for seaming and delivering bags, and severing the chain of stitching between the bags.

As herein shown, the apparatus comprises a bench or table having a series of sewing machines for seaming bags arranged thereon, a guiding chute for each pair of machines, having a guiding wall adjacent to each machine, the walls being adapted to deflect the seamed bags to a common opening, which also has oppositely deflected walls for deflecting the bags into another chute, the latter being also connected in a similar way with the delivery opening from another set of sewing machines, this chute being arranged on the floor below the sewing machine table, so that the seamed bag from the entire series of machines supported on the table may be delivered to the floor below in one pile, and there the proper disposition made of them.

While the mechanism herein illustrated is one which is deemed desirable and convenient for the purposes of carrying out the invention, it will be understood that various modifications and changes may be made, without departing from the spirit of the invention.

So far as the device for feeding the sacks is concerned, the ordinary sewing machine feed is the one that would generally be used for this purpose, but it will be understood that other devices could be used for accomplishing this purpose.

The invention consists in the matters hereinafter described and referred to in the appended claims.

Said invention is illustrated in the accompanying drawings, in which,

Figure 1 is a plan view of an apparatus embodying the invention; Fig. 2 is a front elevation, Fig. 3 is an end view, partly in section; and Fig. 4 is a detail view, illustrating a form of cutting mechanism used in con-

nection with the sewing heads to sever the chain of stitching between any two successive bags.

In these drawings, A represents a supporting framework or table upon which are supported any suitable number of machines B, for seamming bags. These machines are operated from the usual line shaft C, supported in uprights a, on the floor; or in any other suitable way.

As shown in Fig. 4, I use in connection with each sewing machine, a cutting apparatus for severing the chain of stitching between any two successive bags. This cutting apparatus comprises as herein shown, a continuously running knife member, operated from the main shaft of the sewing machine in any suitable manner, and co-operating with a stationary member. The cloth plate of the sewing machine has in rear of the needle and feeding mechanism, an elongated slot, so arranged that when a bag is fed off from the machine, the chain of stitching between it and the succeeding bag will be drawn into the slot 1, in the cloth plate, and into the path of movement of the knife blades 2, 3, the knife blade operating to sever the chain. This particular form of cutting device forms no part of the present invention, but is simply shown by way of illustration, and as forming an important feature in the combination. It is, however, shown, described and claimed in an application filed by Dudley S. Seymour, Jan. 2, 1906, Serial No. 294,255.

In rear of the bed plate of each machine, is a wall D inclined downwardly, the walls of each set of two machines being inclined toward each other, forming an inclined chute E, extending down as far as the floor. From the point b two of the chutes E, incline toward each other, meeting in the vertical chute F below the floor, through which the bags are delivered to the floor below, where proper disposition is made of them.

Having thus described our invention, what we claim as new and desire to secure by Letters Patent, is:—

1. The herein described apparatus for making sewed articles including in combination a work table, a sewing machine mounted thereon, a cutting mechanism for severing the chain of stitches between the sewed articles carried by said machine and located at the rear edge of said table so that

as the sewed articles are fed from the table, the weight of said article will draw the chain of stitches into said cutter; substantially as described.

- 5 2. The herein described apparatus for making sewed articles including in combination a work table, a sewing machine mounted thereon, a cutting mechanism for severing the chain of stitches between the articles
10 carried by said machine and located at the rear edge of said table, so that as the sewed articles are fed from the table, the chain of stitches is positioned in said cutter, a guiding channel for receiving said sewed articles
15 having one of its walls extending beneath the said work table so that said sewed articles will be fed from the said table to said guiding channel.
3. The herein described apparatus for
20 making sewed articles including in combination a work table, a plurality of sewing ma-

chines mounted on said work table, a cutting mechanism for each machine for severing the chain of stitches between sewed articles, said cutting mechanism being located at the rear 25 edge of said table so that as the sewed articles are fed from the table the chain of stitches will be positioned in said cutter, a guiding chute or channel for each set of two machines so located relative to said machines 30 that said sewed articles are fed directly into the same and a common guiding chute or channel into which two of the first named guiding chutes or channels lead; substantially as described.

In testimony whereof we affix our signatures, in presence of two witnesses.

CHESTER McNEIL.
DUDLEY S. SEYMOUR.
